FIG. 6.

INVENTOR.

George E. Adams

UNITED STATES PATENT OFFICE.

GEORGE E. ADAMS, OF PROVIDENCE, RHODE ISLAND.

GLOVE-FASTENER.

SPECIFICATION forming part of Letters Patent No. 275,796, dated April 17, 1883.

Application filed February 14, 1883. (No model.)

To all whom it may concern:

Be it known that I, GEORGE E. ADAMS, of the city and county of Providence, in the State of Rhode Island, have invented a new and useful Improvement in Glove-Fasteners, of which the following is a specification, reference being had to the accompanying drawings.

Figure 1 is a plan of my invention with the glove open. Fig. 2 is a plan of my invention with the glove secured. Fig. 3 is a sectional view through the line *x* *x*, showing the engagement of the parts. Fig. 4 is a top view of the loop. Fig. 5 is a top view of the catch. Fig. 6 is a plan of my invention, showing the glove secured by means of one loop and one catch.

My invention relates to glove-fasteners designed to secure the glove about the wrist; and it consists of a cord or chain, upon which are secured beads or balls, equidistant or nearly equidistant from each other, and which is passed through a series of loops or eyes sufficiently large to admit of the free passage of the cord, but too small to receive the beads. The loops are attached to the exterior of the glove, near one of the edges of the slit or opening, parallel or nearly parallel therewith, each end of said cord projecting or extending some distance beyond the end loops. Upon the opposite border, and parallel or nearly parallel therewith, are secured catches greater in number by one than the loops, and equal in number to the beads, designed to receive and secure the latter. The cord is inclosed within the loops in such manner that a bead appears upon either side of each loop.

The cord or chain *a* may be made of silk, metal, or other suitable material.

The beads *b*, composed of metal or other material, are pinched upon or otherwise immovably secured to the cord. Each bead is furnished with a tassel, *c*, or other appendage, which facilitates the fastening of the glove.

The loop *d* may be cut out in one piece. It may be furnished with prongs or projections *d'* and *d''*. The prong *d'* is turned over upon the base of the loop, whereby an eye is formed, within which is secured the cord *a*. It may be fastened to the glove by passing the prongs *d''* through the material of the glove, and turned over upon a washer or ring on the in-

ner surface of the glove, composed of metal or other material, whereby the loop *d* is secured to the glove. The catch *e*, composed of metal or other material, may be cut in one piece, and may be secured to the glove in the same manner as the loop. The tongue or lip *e'* is punched up in the shape of a section of a sphere, or of a shape to properly fit upon the surface of the bead, and is of just sufficient size to receive and partially inclose the latter. The tongues *e'* of the end catches, Fig. 1, are furnished with slots *e''*, designed to receive the end beads.

Fig. 6 shows a glove secured by means of one loop and one catch only. In such case the catch may be cut out in one piece, as before; but two tongues or lips *e'* are produced therein instead of one, both of which are slotted to receive the beads *e*, and none except the two end beads are attached to the cord. The beads are secured to the catches by taking the tassels *c* between the thumb and finger, pulling the same over and beyond the catches until the beads *b* are caught and secured by the tongue *e'*. The securing of each and every bead, as described, constitutes a complete fastening in itself. The securing of each subsequent bead operates in drawing the edges of the opening of the glove closer together. When all the beads are thus secured the edges of the opening of the glove practically meet. The beads, when secured, bear not only upon the inner surface of the tongue *e'*, but also upon the edge of the aperture in the base of the catch *e*. It is thereby so thoroughly secured that it will not slip or drop out when loosened, and cannot be disengaged by lateral pressure.

I am aware that gloves have been fastened by means of a cord engaged to a system of hooks secured on either edge of the slit or opening; but a glove is thus fastened very insecurely, as there is no device for securely engaging the free end of the cord. The hooks in such fastenings are so constructed that they present at all times a rough or ragged surface, which is apt to catch and tear any delicate material with which it comes in contact. Both of these difficulties are remedied in my invention. If the end of the cord should be loosened, the glove would still remain securely fastened. If any one or more of the beads

should become detached, the remainder would still secure the glove, as before explained; but, as a matter of fact, it would be difficult to accidentally detach the beads from the catches, 5 as they fit closely therein, and as the tongue must be slightly sprung whenever the bead is secured or detached.

When the glove is secured the outer surfaces of the catches are rendered comparative-
10 ly smooth. The tongue or lip of the catch, being globular, like the bead, and of just the size to partially inclose the latter, presents, together with the bead, practically one smooth surface, therein differing from the hooks employed in
15 many other fastenings.

It is obvious that the beads, instead of being oval or globular, may be made in any form desired, the lip of the catch being formed to correspond therewith.

20 I claim as a novel and useful invention and desire to secure by Letters Patent—

1. In a glove fastener, the cord or chain *a*, provided with the beads *b*, the loops *d*, secured to the outer surface of the glove along one of the edges of the slit—preferably upon the outer 25 edge—adapted to receive the cord, and the catches *e*, secured upon the outer surface of the glove along the inner or opposite edge of the slit, provided with tongues or lips *e'*, of a shape and size to receive and secure the beads, 30 all combined substantially as and for the purpose described.

2. The combination of the cord or chain *a*, carrying beads *b b*, with the loops *d d* and the catches *e e*, having lips or tongues *e'*, adapted 35 to receive the beads, substantially as shown and described.

GEORGE E. ADAMS.
